UNITED STATES PATENT OFFICE.

FREDERICK E. KEY, OF ST. LOUIS, MISSOURI, ASSIGNOR TO KEY BOILER EQUIPMENT COMPANY, OF EAST ST. LOUIS, ILLINOIS, A CORPORATION OF MISSOURI.

BOILER PLUG.

Application filed April 8, 1921. Serial No. 459,794.

To all whom it may concern:

Be it known that I, FREDERICK E. KEY, a citizen of the United States of America, and a resident of the city of St. Louis, in the State of Missouri, have invented certain new and useful Improvements in Boiler Plugs, of which the following is a full, clear, and exact description, reference being had to the accompanying drawings, forming a part of this specification.

This invention relates to improvements in boiler plugs, the main object being to produce a highly efficient means for forming an absolutely tight seal at the opening to be closed. Another object is to produce a plug of this kind which is not liable to be unseated by the pressure in the boiler. A further object is to provide an efficient boiler plug having a number of different elements, all of which can be very easily applied to and removed from a boiler.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims hereunto appended.

Fig. I is an elevation showing the inner face of a boiler wall and the inner end of the plug.

Fig. II is a vertical section of the elements shown in Fig. I.

Fig. III is a detail view suggesting the manner in which the spreader can be inserted from the outside of the boiler.

Fig. IV is an enlarged fragmentary section showing the inner margin of the sealing member as it appears before the tightening operation.

Fig. V is a view similar to Fig. IV, showing the inner margin of the sealing member wedged between converging faces in the hole to be closed.

1 designates a boiler wall provided with a tapered hole 2 adapted to be closed by my boiler plug. To illustrate one form of the invention I have shown a plug comprising a sealing member A, a closure member B, a stud C extending from the closure member, and a thrust member in the form of a nut

D mounted on the outer end of the stud and adapted to engage the outer end of the sealing member A.

The closure member B is in the form of a hollow head rigidly secured to the stud C and having a tapered face 3 providing a spreader for the inner margin of the sealing member A. Oppositely disposed lateral flanges 4, extending from the closure member B, lie within the boiler and engage the inner face of the boiler wall 1, as shown by Figs. I and II.

The hole 2 in the boiler wall is preferably tapered, and the tapered face 3 of the closure member B lies at an angle to the tapered face of the hole to provide converging faces between which the sealing member A is wedged as will be presently described.

The outer end of the sealing member A is engaged by the nut D while the annular inner margin of the sealing member lies entirely within the hole 2, where it is interposed between and in contact with the converging tapered faces of the hole and the closure member 3. By referring to Fig. II it will be seen that the nut D may be tightened on the stud 5 with the result of forcing the sealing member A toward the boiler wall 1. While this occurs, the inner margin of the sealing member will be firmly wedged between the tapered face 3 and the tapering face of the hole.

The sealing member A is preferably made of relatively soft metal, for example soft steel, and the annular groove is formed in the inner end face of the sealing member so as to provide yieldable sealing flanges 5 and 5'. This groove is preferably V-shaped to provide walls which diverge toward the inner end faces of the sealing member.

In tightening the thrust nut D, the sealing member A will tend to turn with the nut, and a movement of this kind is undesirable, for the nut should not impart rotary motion to the sealing member. Therefore, the tapering faces at 2 and 3 may be so formed that the flange 5 will primarily engage the tapered face of the hole, as shown by Fig. IV, while the flange 5' is separated from the tapered face 3. This will provide an initial frictional engagement between the sealing member and the boiler wall which will tend to prevent rotation of the sealing member A, and as the nut is tightened, the

friction is increased so as to positively prevent rotation of the sealing member relative to the boiler wall.

- All of the parts can be applied and removed from the outside of the boiler. The flanges 4 on the closure member B will pass through the hole 2 when the members B and C are tilted and properly manipulated as suggested by Fig. III, and all of the other parts can be very easily applied from the outside of the boiler. However, the stud C and closure member B must be held and supported while the members A and D are being applied from the outside of the boiler. A detachable operating member, or holding member, in the form of a rod 6 (Fig. III) is screwed into the outer end of the stud to provide an extended handle over which the sealing member A and nut D may be passed when these members are applied from the outside of the boiler. To appreciate this feature, it should be understood that the closure member B must be held so that it will not fall into the boiler while the members A and D are being removed. The stud C is grasped by one hand while the members A and D are slipped over the extended handle 6, and thereafter, the handle 6 is grasped until the nut D is interlocked with the threads on the stud. The extended handle 3 is then removed from the device.

The seal is formed at the inner margin of the sealing member A, and this margin is subjected to the boiler pressure, but such pressure cannot displace the sealing member. Instead of relying upon friction at the inner margin of the sealing member to prevent displacement thereof, the sealing member is positively anchored as follows:

- The flanges 4 on the closure member B cooperate with the inner face of the boiler wall to prevent outward displacement of said closure member, and since the stud C is rigidly secured to the closure member B, the nut D will cooperate with the sealing member A to prevent outward displacement of the sealing member when the latter is subjected to the boiler pressure.

It is important to note that the inner margin of the sealing member A is firmly wedged between the converging tapered faces at 2 and 3, and that the yieldable flanges 5 and 5' are firmly seated on these converging faces so as to form an absolutely tight and leak-proof seal. At the beginning of the sealing operation, the sealing member A is placed in the position suggested by Fig. IV, wherein its yieldable sealing flange 5 engages the tapered face of the hole 2, while the flange 5' lies very close to the tapered face 3 of the closure member B. As the threaded nut D is tightened, the yieldable sealing flanges 5 and 5' gradually move to the positions shown by Fig. V. These yieldable sealing flanges are thus forced toward

each other by contact with the tapering faces in the hole, and said flanges are firmly seated on the converging faces between which they are tightly wedged. The wedging action at these yieldable sealing flanges compensates for any slight depressions, or irregularities, which are usually found in the face of the hole or in the tapered outer face 3 of the closure member B. The yieldable annular flange 5 is contracted by the wedging action while the yieldable flange 5' is expanded, and the annular groove between the flanges permits them to move toward each other.

It is an advantage to form this groove with walls which diverge toward the inner end face of the sealing member A. This device is intended to be reused a number of times, and it is removable from the boiler. The sealing member A can be readily withdrawn from the converging tapering faces when the nut is removed. However, after a long period of use, the groove between the flanges 5 and 5' may become filled with hard mineral salts, carbon, or other very hard solid matter. In this event, when the flanges 5 and 5' are bent toward each other, the hard solid matter will be freely forced out of the V-shaped groove between the flanges. It will thus be understood that accumulations of hard solid matter will not interfere with the operation of wedging the yieldable sealing flanges between the converging tapered faces.

I claim:

1. In a closure for tapered holes, a closure member adapted to lie in the tapered hole, said closure member having a tapered outer face adapted to lie opposite to the tapered wall of the hole to be closed, so as to provide converging tapering faces in the hole, a sealing member having an inner margin adapted to lie between said converging tapering faces, said inner margin having a groove in its end face to provide a contractible outer flange to contact directly with the tapered face of the hole and an expandable inner flange contacting directly with the tapered face of said closure member, and means whereby said flanges are wedged between and forced toward each other on said converging faces.

2. In a closure for tapered holes, a closure member adapted to lie in the tapered hole, said closure member having a tapered outer face adapted to lie opposite to the tapered wall of the hole to be closed, so as to provide converging tapering faces in the hole, a sealing member having an inner margin adapted to lie within the hole, said inner margin having a groove in its end face to provide inner and outer yieldable flanges adapted to lie between and bear directly against said converging faces, said outer flange being contractible on the tapered face of the hole and said inner flange being ex-

pansible on the tapered face of said closure member, and means whereby said yieldable flanges are forced toward each other on said converging faces, said means including a 5 rotary thrust member whereby the inner margin of said sealing member is forced into said opening, said outer yieldable flange being primarily engaged with the tapering face of the hole to prevent rotation of the 10 sealing member while the other yieldable flange is separated from the closure member.

3. In a closure for tapered holes in boiler walls, a tapered spreader comprising a head having a tapered portion located 15 within the hole to be closed, the largest diameter of said tapered portion being smaller than the diameter of the tapered hole, said spreader also having flanges adapted to pass through the hole and engage the 20 inner face of the boiler wall to prevent outward displacement of the spreader, the spreader taper being at an angle to the tapered face of the hole so as to provide oppositely disposed converging faces, an

annular sealing member having its inner 25 margin entirely within the hole to be closed, the outer margin of said sealing member being extended from the wall of the boiler, said inner margin of the annular sealing member having a V-shaped groove in its end 30 face providing tapering yieldable annular flanges which lie between said converging faces of the hole and spreader, the reduced edge of one of said tapering flanges being in direct contact with the tapering face of 35 the hole while the reduced edge of the other tapering flange is in direct contact with the tapering face of the spreader, a screw-threaded stud extending outwardly from said spreader, and a nut mounted on said stud and engaging the outer face of said sealing member, the latter being movable into the hole in response to rotation of the nut so as to force said yieldable flanges toward each other on said converging faces.

In testimony that I claim the foregoing I hereunto affix my signature.

FREDERICK E. KEY.
